UNITED STATES PATENT OFFICE.

FRED ALBERTH SEBENSTE, OF HAMMOND, INDIANA.

TOBACCO-PIPE.

1,290,791.

Specification of Letters Patent.

Patented Jan. 7, 1919.

Application filed June 13, 1917, Serial No. 174,509. Renewed December 9, 1918. Serial No. 265,962.

To all whom it may concern:

Be it known that I, FRED A. SEBENSTE, a citizen of the United States, residing at Hammond, in the county of Lake and State 5 of Indiana, have invented certain new and useful Improvements in Tobacco-Pipes, of which the following is a specification.

This invention relates to improvements in tobacco pipes. One object is to provide a 10 pipe that is so constructed as to afford a sanitary smoke as the smoke passes from the bowl to the smoke passage in the stem without carrying with it any portion of the condensed nicotine or other deleterious 15 residuum. A further object is to provide a pipe in which tobacco cannot possibly clog the stem, and in which the stem is at all times retained absolutely free from ash from the pipe bowl. A further object is 20 to provide a pipe provided with a partitioned residue compartment in which the liquid residuum and the dry or ash residuum are kept separate, said compartment being readily removable from the pipe to permit 25 it to be thoroughly and readily cleansed. With the foregoing and other objects in view the invention consists in the combination and arrangement of parts to be hereinafter fully described, pointed out in the 30 appended claims and illustrated in the accompanying drawing which forms a part of this specification.

The illustration is a longitudinal sectional view through a pipe constructed according 35 to my invention.

The reference numeral 1 denotes the bowl of the pipe which is threaded for connection with the neck portion 2 which is likewise threaded for connection with the cylindrical 40 jacket 3 which is threaded for engagement with the cap 4. The neck portion 2 is formed with an inner annular shoulder 5 whereon a perforated metal disk 6 is seated and retained rigidly in position by an inner 45 annular shoulder 7 formed by the inner termination of the pipe bowl 1. Within the jacket 3 I provide a block 8 having a depending leg 9 that rests upon the cap 4 and divides the said block into separate compartments 10, 11, said leg dividing one straight face of the block into faces 12, 13. The opposite side of the block 8, with relation to the faces 12, 13, comprises the beveled surface 14 which extends from the 55 straight surface 15 to the straight surface 16, said surfaces being disposed in parallel

planes. One edge of the block 8 is formed with a threaded recess 17 which is positioned in alignment with a threaded aperture 18 in the jacket 3 when the leg 9 of said block 60 rests upon the cap 4, said threaded portions 17, 18 being adapted to receive the threaded end of the stem 19 which is provided with the detachable mouthpiece 20. The block 8 is formed with a duct 21 that leads from 65 its surface 15 to the recess 17 and is in alignment or register with a duct 22 formed in the stem 19 when the same is in engagement with said block and jacket. Another duct 23 in block 8 connects the cap compartment 10 with a duct 24 in the stem, said duct 24 and the aforesaid duct 22 of stem 19 merging into the duct 25 of the mouthpiece. The block 8, further, is provided with a duct 26 that leads from its surface 70 16 to the face 12 thereby communicating with the compartment 11 of the cap 4.

Referring again to the neck 2 the same is formed with a projection 27 formed with a heel 28 that rests upon the surface 15 of 80 block 8 and with a lip 29 that projects over the duct 21, said lip being parallel with the beveled surface 14 and spaced above the same. A sack-shaped screen cup 30 is secured to the disk 6 and depends below the 85 same into the jacket 3 terminating immediately above the beveled surface 14 of the block 8. The ashes from the burning tobacco in the bowl 1 may, in small part, sift through the disk 6 into the cup 30 from 90 which it may drop upon the surface 14 and work its way, through gravity, to and through the duct 26 into the cap compartment and any juices from fresh tobacco will, in like manner, find its way into this compartment. The lip 29 serves as an effectual 95 barrier to prevent ashes and tobacco from working their way into the stem 19 through the duct 21. Saliva or other moisture from the stem of the pipe will find its way, 100 through the duct 24, to the cap compartment 10. The compartments 10, 11 may be readily cleansed by removing the cap 4 from the jacket. The smoke from the tobacco finds its way to the smoker's mouth through the 105 disk 6, screen cup 30, duct 21, duct 22 and duct 25. The smoke can in no manner pass through either of the residue chambers 10 or 11. It is obvious that various changes 110 may be made in the details of construction, and various materials may be used for forming the parts of the pipe without departing

from the spirit and scope of the invention as defined in the claims.

What is claimed is:

1. In a tobacco pipe, an apertured jacket, a cap at one end of said jacket, a neck at the other end of said jacket, a recessed block within said jacket whereby the same is divided into separate compartments, said block being formed with ducts leading to said compartments, a stem engaging with the apertured portion of said jacket and the recessed portion of said block, said stem being formed with ducts in alinement with the ducts in said block, an apertured disk carried by said neck, a screen cup carried by said disk and disposed within said jacket above said block, a bowl carried by said neck above said disk, and a mouth piece for said stem.
2. In a tobacco pipe, a jacket, a cap at one end of said jacket, a neck at the other end of said jacket, a block disposed within said jacket and formed with one beveled face, a leg integral with said block and bearing upon said cap and serving as a partition for one end of said jacket to form therein two separate compartments, a stem threaded into said jacket and block, said stem being formed with two separate ducts, said block being formed with ducts leading into said separate compartments and to the ducts of said stem, a perforated disk carried by said neck, a screen cup carried by said disk within said jacket above the beveled face of said block, a bowl carried by said neck above said disk, and a mouthpiece for said stem.
3. In a tobacco pipe, a jacket, a cap at one end of said jacket, a neck at the other end of said jacket, a block disposed within said jacket and formed with one beveled face, a leg integral with said block and

bearing upon said cap and serving as a partition for one end of said jacket to form therein two separate compartments, a stem 45 threaded into said jacket and block, said stem being formed with two separate ducts, said block being formed with ducts leading into the said separate compartments and to the ducts of said stem, a guard for one of the ducts of said stem, a perforated disk carried by said neck, a screen cup carried by said disk within said jacket above the beveled face of said block, a bowl carried by said neck above said disk, and a mouthpiece 50 for said stem.

4. In a tobacco pipe, a jacket, a cap at one end of said jacket a neck at the other end of said jacket, a block disposed within said jacket and formed with one beveled 60 face, a leg integral with said block and separating the same from said cap whereby one end of said jacket is divided into two separate compartments, a stem threaded into said jacket and block, said stem being formed with two separate ducts, said block being formed with ducts leading into the said separate compartments and to the ducts of said stem, a guard for one duct of said block integral with said neck, a perforated disk carried by said neck, a screen cup carried by said disk within said jacket above the beveled face of said block, a bowl carried by said neck above said disk, and a mouth-piece for said stem.

In testimony that I claim the foregoing as my own I have hereto affixed my signature in the presence of two subscribing witnesses.

FRED ALBERTH SEBENSTE.
